ABSTRACT: A portable conveyor having rollers in its upper surface for sliding a toolbox or the like into a space such as one under a cabinet. The conveyor is hinged intermediate its ends so that the portion of the conveyor projecting from the space may be folded vertically and locked in that position.

FIG. 5

CONVEYOR-TYPE FOLDUP TOOL CHEST BASE

SUMMARY

This invention is for the purpose of easy handling and storing or positioning of tool chest so that it will not take up valuable space and still be easily accessible. This base is a conveyor-type foldup mechanism of light weight, adjustable, and portable characteristics. The base permits chest to be placed in ordinarily awkward places such as: under cabinets, benches, or rear deck sides of automobiles inside the trunk. Simply roll chest under such places on conveyor base and then fold up base half to save space.

BRIEF DESCRIPTION OF VIEWS

Fig. 1. This is a top view of base showing nearly all elements. Base folds in center by use of hinges to permit space saving and base is adjustable on the ends to accommodate most sizes of tool chests.

FIG. 2. This is a side view showing leg supports and adjustability of foldup side of base when it rests in horizontal position.

FIG. 3. This is a partial view of roller angle rails showing rollers and protective guide strip on inside vertical leg of roller angles.

FIG. 4. Here is a cross-sectional view of roller angle rail and protective strip.

FIG. 5. This is a partial view showing adjustable slotted angles and secure strap handle.

DETAILED DESCRIPTION

Conveyor-type foldup tool chest base FIGS. (1, 2, 3, 4 and 5), is made up of the following parts:

- 1—End adjustable slotted angles
- 2—Side roller angle rails
- 3—Roller
- 4—Roller shaft pin
- 5—Roller bearing
- 6—Protective guide strip

7—Hinge

8—Secure strap handle (drawer pull type)

9—Stationary leg

10—Stud leg support block

11—Locknut

12—Stud leg

13—Eye rivet

14—Shoulder rivet

15—Hook

16—Roundhead bolt

17—Flathead countersunk rivet

18—Roundhead bolt with lockwasher and nut

19—Roundhead rivet

20—Rubber spacer with recess for bolt

21—Stud leg plastic tip

22—Protective strip rivet

23—Secure strap

24—Roundhead bolts

I claim:

20. 1. A portable conveyor having rollers in its upper surface for sliding a tool chest or the like into a space extending upwardly from a surface a distance at least equal to the height of the conveyor and toolbox, said conveyor comprising two U-shaped supporting members, hinged together at the ends of

25 the arms of the U, said members adapted to lie in an extended position on said surface with one of said members in said space, for sliding said toolbox on said conveyor into said space to a position entirely on said one member, the other of said members adapted to fold to a predetermined rotated, locked position.

2. The conveyor according to claim 1 in which the width of the conveyor is adjustable.

3. The conveyor according to claim 1 having side guides and provided with supporting legs at least some of which are adjustable.

35 4. The conveyor according to claim 1 having a means of securing chest or the like in relatively rigid predetermined position.

UNITED STATES PATENT OFFICE
CERTIFICATE OF CORRECTION

Patent No. 3,572,485

March 30, 1971

Reese Wesley Hardin

It is certified that error appears in the above identified patent and that said Letters Patent are hereby corrected as shown below:

Column 2, after line 18, insert -- End cross pieces (1) are made of slotted angle to permit adjustment for various length tool chests and roundhead bolts (18) secure slotted angles (1) to ends of roller angle rails (2). Side roller angle rails (2) have slots cut in horizontal leg for roller assembly (3, 5) and holes drilled for roller shaft (4). Protective plastic strip (6) provides for chest protection and guide. It is fastened by rivets (22) Figure 3, which fit into strip recess holes. Base is joined with hinges (7) which are fastened by rivets (19). Stationary legs (9) are fastened to roller angle rails (2) by flat head countersunk rivets (17). Rubber spacer (20) Figure 2 is secured to leg (9) by roundhead bolts (16). If base is used for stationary application, a shorter bolt like (16) is used in inverted position with head fitting into rubber spacer (20) recess and nut on top of stationary leg (9). Stud leg support block (10) is secured to roller angle rails (2) by flathead countersunk rivets (17). Stud leg (12) is held in position by lock nuts (11). Eye rivet (13) is for hook (15) which holds fold-up side of base in vertical position. A shoulder rivet (14) holds hook (15) in place on roller angle rail (2). Plastic tips (21) Figure 2 go on bottom of stud legs (12). A secure strap (23) Figure 2 is attached to secure strap handle (8). Secure strap handle (8) is of the drawer pull type. Roundhead bolts (24) secure end slotted angles (1) together and fastens strap handle (8) to slotted angles (1).

Signed and sealed this 13th day of July 1971.
